UNITED STATES PATENT OFFICE

157,483

CIGARETTE PACKAGE HOLDER

Donald Franklin, Chicago, Ill., assignor to Donald Franklin and Stephens Franklin, co-partners, doing business as Deluxe Engraving Co., Chicago, Ill.

Application July 15, 1949, Serial No. 3,934

Term of patent 7 years

(Cl. D85—2)

To all whom it may concern:

Be it known that I, Donald Franklin, a citizen of the United States and a resident of Chicago, county of Cook, and State of Illinois, have invented a new, original, and ornamental Design for a Cigarette Package Holder, of which the following is a specification, reference being had to the accompanying drawing, forming a part thereof, in which Fig. 1 is a perspective view of a cigarette package holder, showing my new design; Fig. 2 is a view in elevation of one side of the holder; Fig. 3 is a view in elevation of the side opposite that shown in Fig. 2; Fig. 4 is a top view of the holder and Fig. 5 is a bottom view of the holder.

I claim:

The ornamental design for a cigarette package holder, substantially as shown.

DONALD FRANKLIN.
